VARIABLE SPEED ROTARY SPRINKLER

William A. Buckner, Fresno, Calif.

Application December 28, 1937, Serial No. 182,055

12 Claims. (Cl. 299—69)

This invention relates to rotary water sprinklers of the opposed nozzle slow motion type, and particularly represents improvements over the sprinklers of this type shown in my copending 5 applications Serial No. 154,791 filed July 21, 1937, and Serial No. 155,461 filed July 24, 1937.

In both these previous devices the operating mechanisms while effective for their purpose, were so positioned and arranged that they could 10 not well withstand the rough handling to which such sprinklers are apt to be subjected, and as a result such mechanisms were too easily bent or distorted so as to jam or otherwise fail to function efficiently. The principal object of the present 15 invention therefore is to provide a rotary sprinkler having a rotation imparting mechanism so disposed as to better able to withstand rough usage, and at the same time such mechanism is more compact and closer to the rigid and strong 20 sprinkler head than in the previous devices, thereby further lessening the likelihood of damage being done thereto.

A further object is to provide a means whereby if desired, the sprinkler head may be given 25 rotary impulses in opposite directions alternately while keeping the impulses in one direction always the strongest, so that the sprinkler will actually turn in one direction.

A further object of the invention is to produce 30 a simple and inexpensive device and yet one which will be exceedingly effective for the purpose for which it is designed.

These objects I accomplish by means of such 35 structure and relative arrangement of parts as will fully appear by a perusal of the following specification and claims.

In the drawing similar characters of reference indicate corresponding parts in the several views.

Figure 1 is a side elevation of my improved 40 sprinkler.

Figure 2 is a top plan view of the same.

Figure 3 is a fragmentary transverse section on line 3—3 of Fig. 1.

Figure 4 is a similar view on line 4—4 of Fig. 1.

Figure 5 is a fragmentary plan section on line 5—5 of Fig. 1.

Referring now more particularly to the characters of reference on the drawing, the sprinkler comprises a vertical supporting member 1 adapted 50 at its lower end for connection to a water supply pipe. Turnable mounted in and upstanding from this member is a tubular spindle 2 which depends from the base 3 of the sprinkler head. The sprinkler head includes main and auxiliary nozzles 4 and 5 respectively extending in opposed 55

relation from the base 3 of the sprinkler head at an upward angle and having jet elements 6 and 7 respectively at their outer ends.

Extending lengthwise and over the nozzles and following the angular setting thereof is a rigid 5 arm 8, the end portion of which over the nozzle 4 being in the form of a weight as at 9. Substantially centrally between its ends, this arm is formed with a relatively long upstanding sleeve 10, turnable on a stem 11 mounted in the nozzle 10 5 adjacent the vertical axis of the sprinkler head, and disposed at a right angle to the axis of nozzle 5. The arm 8 under the sleeve rests on the boss 12 from which stem 11 projects, so that the 15 arm for its major extent remains clear of the nozzles.

A symmetrical wedge shaped driver or water deflecting element 12, with its sides in substantially vertical planes and with its apex facing the jet 7, is mounted for oscillation on a pin 13 20 depending from arm 8 beyond jet 7. The oscillating movement of the driver is limited by a stop lug 14 on the arm depending into an opening 15 formed at the back of the driver (see Fig. 5). The side faces of the driver are depressed relative to straight lines intermediate their ends as shown at 16. This forms a sort of vacuum 25 pocket behind the water stream from the jet 7 as it strikes either face, causing such water to 30 strike the portion of the face beyond the depression with greater force than would otherwise be the case, and imparting a greater driving action to the element 12.

The arm 8 is normally maintained in a centralized or alined position relative to the nozzles 35 by the following means: Formed in the sprinkler head on top and centrally thereof is a transverse housing 17, in which is slidably mounted a stop pin 18, a compression spring 19 engaging the same, and an adjustable screw 20 engaging the 40 spring. The pin is formed with a shoulder S within the housing, and normally projects from one side of housing 17 a distance determined by said shoulder. The pin at its outer end engages a lug 21 depending from arm 8. When the pin 45 and lug are thus engaged and the arm 8 is at rest, said arm is in alined position.

To move said arm to such position after it has been deflected in a direction away from the stop pin by water striking the driver, I provide a 50 torque spring 22. This is disposed about the hub 10, the lower end being secured on the arm 8 and the upper end being secured on a turnably adjustable collar 23 mounted on the upper end of stem 11 (see Fig. 3). The spring 22 and adjacent parts 55

are enclosed and protected by a removable cap 24.

Mounted for rotary adjustment on the screw 20 outwardly of the housing 17 is a cam 25 positioned in the path of the oscillating movement of the arm 8 toward the corresponding side of the sprinkler.

In operation, when the sprinkler is started and the arm is in its normal aligned or neutral position, water from jet 7 will strike driver 12 on one face 10 or the other, said driver being initially disposed at one end or the other of its oscillating stroke. Assuming that the driver is positioned as indicated in dotted lines in Fig. 5, the arm 8 is swung so that the lug 21 pushes the pin 18 in, and strikes the adjacent end of the housing 17, causing the sprinkler head to be rotated slightly in the same direction as the movement of the arm.

This also jars the arms so that the driver reverses itself in position, and with the rebound 20 movement of the arm due to the action of spring 19 on pin 18, water issuing from jet 7 strikes the other face of the driver 12 as the latter swings across the path of the stream. The arm 8 is then driven in the corresponding direction, increasing the torque of spring 22 until the momentum of arm 8 derived from the water has been overcome. The arm then swings in the opposite direction and past the water stream. Movement of the arm toward the stop pin to impinge 30 another rotative impulse to the sprinkler head is aided by a further impingement of water against the driver.

The main function of the spring 22 is to center the arm 8 relative to the nozzles. The weight of 35 the lever itself is so distributed that under ordinary conditions, or when the sprinkler is upright, the driver will be automatically centered in the stream. The spring is thus only actually necessary to secure this centering if the sprinkler is set 40 at an angle such as to prevent the weighted arm centering itself.

The tension of spring 22 is set relative to that of spring 19 so that the action of said spring 22 will not cause the pin 18 to be depressed.

45 Adjusting the tension of spring 22 (which of course calls for a corresponding adjustment of spring 19) enables the speed of rotation of the sprinkler to be altered.

This is because the greater the initial tension 50 of the spring for instance, the shorter will be the arc through which the arm 8 will swing from the neutral position in a direction away from pin 18 before returning to impart a further rotative impulse to the sprinkler head, and the shorter 55 will be the time between successive impulses. This of course will cause a greater number of impulses to be imparted within a given period and the speed of rotation of the sprinkler head will be correspondingly increased.

60 The cam 25 is for the purpose of enabling the arm 8, with its swing in that direction, to engage the cam as a stop and impart a backward rotative impulse to the sprinkler head. This will only be effective when the spring 22 is set with a relatively 65 weak tension, or when the water pressure is very strong. These latter rotative impulses will never be as strong as those given to the sprinkler in the forward direction or by the lug 21, so that the 70 sprinkler moves with what may be described as one step forward and half step back.

By altering the position of the cam on screw 20, which alters the length of the arc of swing of the arm 8 before it will strike the cam, a 75 quarter-step, or any other fractional rotative im-

pulse, can be given the sprinkler in a backward direction.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure 10 from the spirit of the invention as defined by the appended claims.

Having thus described my invention, what I claim as new and useful and desire to secure by Letters Patent is:

15 1. A rotary sprinkler comprising a sprinkler head mounted for rotation and having a radial nozzle member provided with a jet opening at its outer end, an arm normally extending lengthwise of and above the member, means pivoting said 20 arm on the head for oscillating movement in a substantially horizontal plane on either side of a predetermined neutral position, means between the arm and head to impart a rotative impulse to the latter with swinging of the arm in one 25 direction from a predetermined neutral position intermediate the limits of its oscillating movement, means to return the arm to such position after swinging movement therefrom in either direction, and a water engaging driving element 30 mounted on the arm beyond the outer end of the nozzle member in position to depend into the path of the stream issuing from said jet opening to be engaged by such stream when the arm is in said normal position to impart movement to 35 the arm in one direction or the other.

2. A structure as in claim 1, in which the arm pivoting means comprises a pin mounted on and upstanding from the nozzle member at right angles thereto.

40 3. A structure as in claim 1, in which said arm return means comprises a spring acting on the arm after movement thereof to an impulse imparting position, and another spring acting on the arm after swinging thereof in the other direction from said neutral position.

45 4. A structure as in claim 1, in which said water engaging element comprises a wedge shaped member whose opposite side faces lie in substantially vertical planes and whose apex faces 50 the jet opening, and means mounting the member on the arm for limited oscillating movement in a substantially horizontal plane.

5. A structure as in claim 1, in which said water engaging element comprises a wedge shaped 55 member whose opposite side faces lie in substantially vertical planes and whose apex faces the jet opening, and means mounting the member on the arm for limited oscillating movement in a substantially horizontal plane; said side 60 faces being depressed from straight lines intermediate their ends.

6. A structure as in claim 1, in which said water engaging element comprises a wedge shaped member whose opposite side faces lie in 65 substantially vertical planes and whose apex faces the jet opening, a pivot pin depending from the arm and supporting the element intermediate its ends, said element having an opening beyond the pin, and a fixed relatively small stop 70 on the arm depending into said opening.

7. A structure as in claim 1 with means to limit the oscillating movement of the arm to a short arc of travel in said one direction from said neutral position compared to the arc of 75

travel of the arm possible in the other direction from said neutral position.

8. A structure as in claim 1, with additional means between the arm and head to cause the arm, with a swinging movement in the opposite direction from said neutral position, to impart a rotative impulse to the head in a direction opposite that given to the head with the movement of the arm in said one direction and with a smaller force.

9. A structure as in claim 1, with additional means between the arm and head to cause the arm, with a swinging movement in the opposite direction from said neutral position, to impart a rotative impulse to the head in a direction opposite that given to the head with the movement of the arm in said one direction and with a smaller force; said last named means including a member adjustable and arranged to enable such impulsive force to be altered.

10. A rotary sprinkler comprising a sprinkler head mounted for rotation and having a radial nozzle member provided with a jet opening at its outer end, an arm normally extending lengthwise of and above the member, a stem mounted on and upstanding from the member between the outer end of the member and the axis of the head and relatively close to the latter, the arm being turnable on the stem, a normally advanced

pin projecting at right angles to the nozzle member from one side of the head substantially in line with the axis of the head, a spring advancing said pin, a lug on the arm to engage the outer end of the pin, the arm, when the lug is engaged with the pin and the latter is fully advanced being in longitudinal alinement with the nozzle; said arm being capable of relatively great movement in a direction relative to said alined position away from the pin, another spring between the head and arm placed under increasing tension with the movement of the arm in said last named direction, and an element on the arm beyond the outer end of the nozzle in position to be engaged by the stream issuing from the jet opening and arranged to cause impingement of the water against one side or the other of said element to impart swinging movement of the arm in one direction or the other as the arm swings past the plane of the path of the stream.

11. A structure as in claim 10, in which the last named spring is set to return the arm to said alined position and normally maintain the lug alined with the pin without imparting retractive movement to the latter.

12. A structure as in claim 10, with separate means to separately adjust the normal tension of the springs.

WILLIAM A. BUCKNER.
